UNITED STATES PATENT OFFICE

106,882

DESIGN FOR A SHOE FABRIC OR SIMILAR ARTICLE

John A. Fogarty, Portland, Maine

Application November 30, 1936, Serial No. 66,195

Term of patent 3½ years

To all whom it may concern:

Be it known that I, John A. Fogarty, a citizen of the United States, residing in Portland, in Cumberland County, in the State of Maine, have invented a new, original, and ornamental Design for a Shoe Fabric or Similar Article, of which the following is a specification, reference being had to the accompanying drawing, forming part thereof.

The figure is a plan view of a piece of shoe fabric showing my new design on an enlarged scale in the ratio of 2 to 1.

I claim:

The ornamental design for a shoe fabric or similar article, substantially as shown and described.

JOHN A. FOGARTY.
